UNITED STATES PATENT OFFICE.

FREDERICK HENRY ROYCE AND ERNEST WALTER HIVES, OF DERBY, ENGLAND,
ASSIGNORS TO ROLLS-ROYCE LIMITED, OF DERBY, ENGLAND.

PRIMING DEVICE FOR INTERNAL-COMBUSTION ENGINES.

1,326,098.

Specification of Letters Patent. Patented Dec. 23, 1919.

Application filed June 18, 1917. Serial No. 175,340.

To all whom it may concern:

Be it known that we, FREDERICK HENRY ROYCE, a subject of the King of England, residing at Derby, in England, and ERNEST WALTER HIVES, a subject of the King of England, residing at Derby, in England, have invented certain new and useful Improvements in Priming Devices for Internal-Combustion Engines, of which the following is a specification.

The present invention relates to priming devices for internal combustion engines, and more especially to priming devices of the type disclosed in the United States patent 15 to Hives, No. 1,206,221, granted November 28, 1916, wherein the float chamber of the carburetor has connected with it a supplemental chamber which, in turn, is in communication with the induction pipe of the engine and is provided with a means for supplying air under pressure to it, so that the liquid fuel will be ejected from the aforesaid chamber into the induction pipe in the form of a spray.

According to the present invention, the priming device is constructed as a separate or self-contained unit of apparatus to be connected up to the engine, such unit including a fuel-supply tank which is distinct 25 from the float-tank and to which the supplemental chamber is connected, the latter preferably having the form of a U-shaped pipe or passage. This chamber or passage is connected with the induction pipe of the engine and, also, with the air-supply means for the purpose above stated, the system of pipes employed being equipped with valves for controlling the connection of the said chamber with the various pipes. The invention, 30 therefore, comprehends, and has for its object, the provision of the improved features just enumerated, as well as others herein-after specified, considered both structurally and from the standpoint of relative arrangement.

The invention is applicable, though not exclusively, to structures where the air supply is required for other purposes than the operation of the priming device, and where more than one engine is installed; and in carrying out the invention the supply tank feeds, through a one way valve, the supplemental chamber, the latter being connected by a pipe with the induction pipe or pipes of the engine or engines and directly connected to the air pressure pump (which may

also be used to pump air into the general supply tank where a pressure feed is used, or for other purposes). In the pipe connecting the supplemental chamber to the induction pipe, a valve is introduced whereby said chamber can be connected with the induction pipe of the engine or of any one of the engines, where more than one engine is installed; and (when the air pump is used 60 to put pressure in the general fuel supply tank or for any other purpose) in the pipe connecting the supplemental chamber with the air pump there is also introduced a valve whereby the pump can be connected with the 65 supplemental chamber or with any other tank, pipe or vessel. The valves are of the kind operated by rotating a central shaft or spindle with ports and by-passes formed therein.

An embodiment of the invention is shown in the accompanying drawings, wherein:—

Figure 1 is an elevation of the improved priming device with parts in section.

Figs. 2 and 3 are sections on an enlarged 80 scale through the ports of the two valves the spindles of which are integral.

a designates the liquid fuel reservoir provided with a cover *a*¹, having formed integrally therewith a projection *a*², to which 85 cover the air-pump *b* is detachably connected by means of the nut *b*¹. The air pump valve *b*² (which may be of any desired construction and is shown at the base of the pump) is connected to the pressure- 90 pipe *c*.

In the base of the reservoir *a* is fitted a non-return valve *a*³, which permits of the liquid in said reservoir passing into the supplemental chamber shown in the form of a 95 U shaped tube *d* until such liquid assumes the level of the liquid in the reservoir. The non-return valve *a*³ may be of any desired construction and is shown as a ball-valve. The distributing valves *e* and *f* (which may 100 be mounted in any suitable manner) are carried by the projection *a*² of the cover *a*¹.

The shaft or spindle *e*¹ of the valve *e* is formed with a passage-way *e*² partly axial and partly radial so that on rotation of the 105 valve the pipe *c* can be placed into connection with any of the ports *h*, *h*¹ or *h*² in the valve casing which also contains a by-pass *h*³. The shaft or spindle of the valve *f* (which is a continuation of or otherwise 110 combined with the shaft or spindle *e*¹ of the valve *e*) is formed with a partly circum-

ferential passage j^1 by means of which connection can be made between ports j and j^1 or j^1 and j^2 in the valve casing.

The operation, briefly described, is as follows: The priming fuel contained within the tank a passes through the non-return valve a^3 into the U-shaped pipe d and, on manipulation of the valves e f in one way, communication is established through pipe 10 e with the air pump, so that air under pressure can pass through pipe m and carry the priming fluid from the U-shaped pipe d through pipe n to the priming pipes o and p . By a different manipulation of the 15 valves, the air pump can be placed in communication with either of the pipes l or k for producing pressure in the main fuel tank when a pressure feed is used, or either or both of these pipes may be used to convey 20 the air to some other device in which it is desired to produce pressure.

With the spindles in the positions shown in the drawings the air-pump b is in communication via port h^1 with the pipe l , and 25 by rotating the spindles clockwise through an angle of 90° said air pump can be placed in connection via port h with the pipe k ; and further by rotating the spindles through a further angle of 90° , the pump would be 30 placed in connection via port h^2 with the pipe m and hence with the supplemental chamber d and the pipe n . Thus the supplemental chamber or tube d would be in communication via ports j^1 and j with the priming pipe o , and by further rotation of 90° the air-pump would be in communication via by-pass h^3 and port h^2 with the pipe m and hence with the supplemental chamber d , the pipe n and hence the supplemental 35 chamber being also in connection with the priming pipe p via the ports j^1 and j^2 .

It will be observed, when the air-pump is in communication with either of the pipes l or k , that the priming pipes o and p are 40 cut out. Pipes l and k may be connected up to the main liquid fuel tank or tanks (not shown) or used for any other suitable purpose where air pressure is required.

Liquid fuel may be introduced into the 45 supply tank a by removing the plug a^4 in the cover a^1 .

It is possible to arrange this mechanism without a non-return valve in the base of the reservoir but the same would not work 50 so efficiently when priming owing to the escape of pressure through the liquid in the reservoir a .

What we claim as our invention and desire to secure by Letters Patent of the United 55 States is:—

1. A priming device for internal combustion engines, constructed as a self-contained unit and comprising, in combination, a liquid fuel supply vessel, other than the float 60 tank of the carburetor of the engine; a U-

shaped conduit in communication with said vessel, whereby fuel will flow by gravity to said conduit; a cover for said vessel; an air-pump mounted on said cover; valve casings carried by said cover; valves within said 70 casings having spindles adapted to move in unison; and pipe connections controlled by said valves for effecting communication between the air-pump and said U-shaped conduit and between the latter and the induction pipe of the engine. 75

2. A priming device for internal combustion engines comprising a liquid fuel supply vessel, a U-shaped conduit in communication therewith whereby fluid will flow by 80 gravity to said conduit, a non-return valve between the vessel and conduit, a cover for said vessel, an air-pump attached to said cover, a projecting member on the latter, means carried by said member for effecting 85 communication between the air-pump and the said conduit, pipe connections between the said conduit and the induction pipe of the engine and means for cutting off or connecting the conduit with the induction pipe 90 of any one of a plurality of engines substantially as described.

3. A priming device for internal combustion engines comprising a liquid fuel supply vessel, a supplementary chamber connected therewith, means for supplying air under pressure to the said supplementary chamber, connections between the said chamber and the air pressure supply means, connections between the said chamber and the 95 induction pipes of a plurality of engines and means for cutting out or connecting the chamber with the induction pipe of any one of said plurality of engines. 100

4. A priming device for internal combustion engines, constructed as a self-contained unit and comprising, in combination, an air pump; a U-shaped conduit in communication at one side with said pump and at the other side with the induction pipe of the 110 engine; a liquid fuel supply vessel other than the carburetor of the engine in communication with said conduit between said pump and said induction pipe to feed fuel to the conduit by gravity; and means for controlling the communication between said conduit and said induction pipe. 115

In witness whereof we have signed this specification in the presence of two witnesses.
